SHELF

Theodore Sobel, South Orange, N.J., and Arthur Goldstein, Scarsdale, N.Y., assignors to Butler Industries, Inc., Newark, N.J., a corporation of New Jersey

Filed May 9, 1968, Ser. No. 11,855

Term of patent 14 years

Int. Cl. D6—99

U.S. Cl. D33—3

FIG. 1

FIG. 2

FIG. 3

FIG. 4

FIG. 5

FIG. 6

FIG. 1 is a front perspective view of a shelf embodying our new design;

FIG. 2 is a right end elevational view thereof;

FIG. 3 is a front perspective view of a shelf embodying a modified form of our new design;

FIG. 4 is a right end elevational view of the shelf shown in FIG. 3;

FIG. 5 is a rear-elevational view of the shelf shown in FIG. 1; and

FIG. 6 is a bottom plan view thereof.

We claim:

The ornamental design for a shelf, as shown and described.
